UNITED STATES PATENT OFFICE.

IRVING C. WRIGHT, OF DORCHESTER, AND DAVID P. CUMMINGS, OF NEWTON,
MASSACHUSETTS.

RACKET CASE AND PRESS.

1,027,786.

Specification of Letters Patent.

Patented May 28, 1912.

Application filed November 14, 1911. Serial No. 660,226.

To all whom it may concern:

Be it known that we, IRVING C. WRIGHT and DAVID P. CUMMINGS, citizens of the United States, residing, respectively, at 5 Dorchester and Newton, in the county of Norfolk and State of Massachusetts, have invented certain new and useful Improvements in Racket Cases and Presses; and we do hereby declare the following to be a full, 10 clear, and exact description of the invention, such as will enable others skilled in the art to which it appertains to make and use the same.

My invention relates to receptacles or 15 cases for tennis rackets.

It has for its object to provide a convenient receptacle for a racket which shall contain the means for pressing or keeping the racket in shape while in the case, making, in short, a combined case and press. I 20 accomplish this by providing the article set forth in the following specification and appended claims.

In the accompanying drawing,—Figure 1 25 is a plan view partly broken away; Fig. 2 is a longitudinal, vertical section; Fig. 3 is a sectional detail on line 3—3 of Fig. 1, and Fig. 4 is a sectional detail of a modification illustrating a casing and press for two 30 rackets.

In the drawings, 10 denotes a casing, preferably of metal, which may be covered with a skin or casing of leather or similar material. It will be observed in Fig. 2 that 35 this casing conforms, preferably, to the general contour of a racket. While the sides of the handle part are nearly parallel, the bottom of the casing curves slightly to approach the line of the bottom of the head-section of the casing, while the top of the head-section or cover 11 is gradually inclined. The hinged cover 11 has a reinforcing strip 12, which is preferably of wood or some convenient strong but light material. 40 The cover is secured over the casing by any form of fastening but we prefer the form illustrated in detail in Fig. 3, which is that of a spring clip 13 whose lip takes under the bottom of the casing.

Within the casing are two cross-pieces 45 which together form a press 14. The sectional illustration of Fig. 2 indicates the familiar manner in which the cross-pieces are joined, while Fig. 1 illustrates the sub-

stantially X-shaped piece which they form. 55 Secured to or embedded in one side of the X-shaped press-piece is a metal plate 15 with a threaded sleeve 16 projecting into a corresponding perforation which passes through the center of the press 14. A set- 60 screw or thumb-screw 17 passes through a perforation in the top or cover of the casing and has the customary washers 18, 19. It is the function of this thumb-screw to work in the threaded perforation 16, and to elevate 65 and depress the press 14, compressing or releasing from pressure the head of the racket. When pressure is applied to the center of the X-frame the force is communicated to the ends of the pieces and is, with a certain 70 desirable flexibility, applied to the head of the racket.

The construction described would serve the desired purpose but an additional and more complete effect is produced by the 75 use of springs 20 which are provided to press upon the head of the racket at the points indicated in Figs. 1 and 2. Various arrangements of these springs may be made. In the form illustrated it is secured at one 80 end to the reinforcing strip 12 of the hinged cover 11 and at the other end is a slot 21 which is guided by a pin 22 secured in the reinforcing piece 12. This arrangement permits an easy play of the spring 20 and also 85 permits a ready separation of the parts if desired.

It will also be observed that in the construction illustrated in Fig. 2 the cover exerts a certain pressure upon the head of 90 the frame by the mere act of closing the cover. At the point 23 the reinforcing piece 12 of the cover comes into contact with the top of the X-frame and would by this simple arrangement prevent the distortion of that 95 part of the frame while the springs would serve, as described, to exert pressure on the other end of the head of the racket. This arrangement is advantageous in case the player should neglect to operate the screw 100 17. All of these provisions combined serve effectively to form a press within a case.

In Fig. 4 a modification is illustrated showing a casing and press for holding two rackets. The features are identical with the 105 single form described, excepting that between the two cases is a U-shaped intervening plate 24 by which the pressure applied

to the upper racket is communicated to the curved head of the lower racket. The plate is secured in place by a strip 25.

The utility and convenience of this device 5 is obvious. It enables the player to at once dispose of his racket after playing without the necessity of subsequently removing it and putting it into a press. It also enables him to carry the racket from place to place 10 constantly under pressure until put into use.

We claim:—

1. In a racket-case, the combination of a case having a rigid backing, a press within the case, and means for operating the press 15 to force the racket against the rigid backing.
2. In a racket-case, the combination of a cover, a screw passing through the cover, and a press-frame carried and operated by 20 the screw within the case.
3. In a racket-case, the combination of a receptacle, a screw working through the cover of the case, a free frame composed of cross-pieces within the receptacle and suspended and operated by the screw. 25
4. In a racket-case, the combination of a

cover, a screw passing through the cover, means for dividing the casing into receptacles for different rackets, and a press-frame carried and operated by the screw to apply 30 pressure to all of the rackets.

5. In a racket-case, the combination of a hinged cover, a frame within the case, springs adapted to one end of the cover for exerting pressure upon the frame when the 35 cover is closed, and means for applying additional pressure upon the whole frame.

6. In a racket-case, the combination of a hinged cover, a frame within the case and arranged to lie at the forward end in contact with the cover and the racket, pressure springs at the opposite end, and a central 40 pressure means operating upon the frame.

In testimony whereof we have hereunto signed our names in the presence of two 45 subscribing witnesses.
